United States Patent Office.

THOMAS ST. CLAIR FERRISS, OF NASHVILLE, TENNESSEE.

Letters Patent No. 68,428, dated September 3, 1867.

IMPROVED TRUSS-PAD.

The Schedule referred to in these Letters Patent and making part of the same.

TO ALL WHOM IT MAY CONCERN:

Be it known that I, THOMAS ST. CLAIR FERRISS, of Nashville, State of Tennessee, have invented certain new and useful Improvements in Truss-Buttons; and I declare the following to be a full, true, and exact description of the same, reference being had to the accompanying drawings, and to the letters of reference marked thereon.

Figure 1 represents a plan view of the button.

Figure 2 is a section view of the same.

Figure 3 is an inverted view.

The nature of my invention consists in casting a button in the peculiar shape represented, with a perforated wooden core, for the purpose of retaining any medicated or healing substance.

The manner of making my button is as follows: I first shape any porous wood similar to the form of the button. I then puncture or perforate the core in half a dozen or more places; then place the core in the mould, and cast the metal or button. When cold I remove the button and perforate it through and through in any desired number of places, as seen in the drawing. The button is then secured to a truss by means of a screw, the holes *a* & *a*, in fig. 3, being for this purpose. The medicated or healing substance may then be introduced. Hard rubber could be used, with sponge inserted, to retain the medicated substance, but I prefer the metal and wood, as it is much more cleanly and inodorous.

My button is designed to be applied to any kind of a truss.

Having thus described my invention, what I claim, and desire to secure by Letters Patent, is—

Providing a truss-button or pad with a perforated wooden core, as and for the purpose specified.

T. ST. C. FERRISS, M. D.
